SAMUEL W. HUNTINGTON, OF AUGUSTA, MAINE.

Letters Patent No. 79,125, dated June 23, 1868.

IMPROVEMENT IN DOOR-SPRINGS.

The Schedule referred to in these Letters Patent and making part of the same.

TO ALL TO WHOM THESE PRESENTS SHALL COME:

Be it known that I, SAMUEL W. HUNTINGTON, of Augusta, in the county of Kennebec, and State of Maine, have invented a new and useful Door-Spring, or device for closing doors; and do hereby declare the following to be a full, clear, and exact description thereof, due reference being had to the accompanying drawings, making part of this specification, and in which—

Figure 1 is an inside view or elevation of a door and its frame, while

Figure 2 is a vertical and longitudinal view of the same, with my invention applied thereto.

Figure 3 is a vertical and transverse section of the same, with the door shown as being opened to its fullest extent.

The object of my present invention is to construct a device for causing doors, when left open carelessly, to be closed automatically, and that such device, while performing its required functions noiselessly and effectively, shall be entirely concealed from view when the door is closed.

The invention consists in applying to the hinged edge of the door, and between such edge and its jamb, a cord, tube, or cylinder of vulcanized India rubber, elastic throughout its whole length, which is let into mortises or holes made in such door-edge and jamb and opposite each other, the elastic material being confined at each end within the respective holes, and serving by its contracting force to close the door, and thus the spring, by which the door is closed, serves directly to connect the door and jamb.

In the accompanying drawings, A denotes a door of ordinary construction, and b its frame, the hinges connecting the two being shown at c c.

The holes for reception of the elastic spring are shown at d d', the former being bored into the inner edge of the door, and the latter into the adjacent jamb, and being opposite each other.

The elastic cord or strip is shown at e, with its opposite ends confined in the holes d d' respectively, such elastic strip, when confined therein, being stretched to some extent in order to insure the entire closing of the door under all circumstances.

The operation of the device will be obvious to any one. Upon opening the door, the elastic strip will be distended, and when the hold upon the door is removed, and it is free to turn upon its hinges, will serve, by its contraction, to close the door.

The mouth of the holes or recesses may be surrounded and protected by a metallic plate or socket, m, to prevent wear of the wood, and these plates may also serve to retain the elastic strips in place.

I would remark that in place of applying the elastic strip between the door and its jamb, as shown in the drawings, I have contemplated applying one end of such spring within a hole formed within the door-frame, and to one side of the face of such door, the opposite end of the spring being provided with an eye to hook or clasp upon a hook fixed to the face of the door, thus allowing the spring to be used in connection with the door or not, as occasion or necessity dictates.

One advantage of the above-described device is, that the door, when left open to its fullest extent, will be certain to be retracted and closed.

Another advantage, and an important one, is the fact that it may be produced and applied to almost any description of doors at very small cost, and with very little trouble, and should the elastic strip give out, it may be replaced or screwed in a like expeditious and economical manner.

In addition to these advantages is the fact that the device is entirely out of sight when the door is closed.

In conclusion, I would remark that I am well aware that it is not new to effect the closing of doors, &c., by means of a strip connecting the hinged edge of the door and the jamb, and actuated by a spring. This strip, however, has heretofore possessed no contractile force of its own, but has been retracted within the mortises in the door and jamb by means of spiral or other springs set in such mortises. But in my door-closing device, the strip which connects the door with the jamb constitutes at the same time the spring, by the contractile force of which the door is kept closed. It is elastic throughout its whole extent, and the spring is not, as in other

cases, enclosed entirely within the mortises in the door or jamb, or both. I thus not only produce a device more simple and cheaper than others heretofore used, but one in which more spring-power is contained in less space. The use of metal spiral springs in devices of this class has met with no substantial success, for such springs are not only necessarily costly and cumbersome, but they wear rapidly, and soon require to be replaced. My invention dispenses with the use of any auxiliary springs, and furnishes a combined spring and connecting-strip, which is inexpensive, lasting, and entirely fitted to accomplish the result desired. The spring, connecting-strip, and sockets *m m*, in which it is held, constitute also a door-closing device, which can be readily made and used in any connection where its services are required.

Having thus described the advantages of my invention, and its construction and mode of application, What I claim as novel and of my invention, and desire to secure by Letters Patent of the United States, is as follows:

A spring for closing doors, &c., consisting of a strip or cylinder of vulcanized India rubber, and sockets, *m m*, in which the ends of the same are held, constructed and arranged as described, and applied to the edge of the door and jamb to which the door is hinged in the manner set forth.

S. W. HUNTINGTON.
